(57) CLAIM

The ornamental design for a table, as shown and described.

DESCRIPTION

FIG. 1 is a front perspective view of a table according to my new design;
FIG. 2 is a front elevational view of my new design;
FIG. 3 is a top elevational view of my new design;
FIG. 4 is a side elevational of my new design, the opposing side view being a mirror image thereof;

FIG. 5 is a bottom elevational view of my new design;
FIG. 6 is a back elevational view of my new design;
FIG. 7 is a front perspective view of a second embodiment of my table design;
FIG. 8 is a front elevational view of the second embodiment of my new design, the back view being substantially identical thereto except that no lock plate is included therein;
FIG. 9 is a top elevational view of the second embodiment of my new design;
FIG. 10 is a side elevational of the second embodiment of my new design, the opposing side view being a mirror image thereof;
FIG. 11 is a front perspective view of a third embodiment of my table design;
FIG. 12 is a front elevational view of the third embodiment of my new design, the back view being substantially identical thereto except that no lock plate is included therein;
FIG. 13 is a top elevational view of the third embodiment of my new design;
FIG. 14 is a side elevational of the third embodiment of my new design, the opposing side view being a mirror image thereof;
FIG. 15 is a front perspective view of a fourth embodiment of my table design;
FIG. 16 is a front elevational view of the fourth embodiment of my new design, the back view being substantially identical thereto;
FIG. 17 is a side elevational of the fourth embodiment of my new design, the opposing side view being a mirror image thereof;
FIG. 18 is a top elevational view of the fourth embodiment of my new design; and,
FIG. 19 is a front perspective view of a fifth embodiment of my table design, the remaining views being substantially similar to the third embodiment of my new design, except that the orientation and number of lateral and cross members of the table base vary according to the length and width dimensions of the table.

1 Claim, 6 Drawing Sheets
